[57] CLAIM

The ornamental design for a child carrier, as shown and described.

DESCRIPTION

FIG. 1 is a front perspective view of a child carrier showing my new design;

FIG. 2 is a right side elevational view thereof, the left side being a mirror image of that shown;

FIG. 3 is a top plan view thereof;

FIG. 4 is a bottom plan view thereof;

FIG. 5 is a front elevational view thereof; and

FIG. 6 is a rear elevational view thereof.

The broken line illustration of wheels shown in FIGS. 1 through 6 are for illustrative purposes only and form no part of the claimed design.

FIG. 1

FIG. 2

FIG. 3

FIG. 4

FIG. 5

FIG. 6
